(57) **CLAIM**

The ornamental design for tire tread, as shown and described.

DESCRIPTION

FIG. 1 is a perspective view of a tire tread;

FIG. 2 is side view thereof; and,

FIG. 3 is a front view thereof.

The broken line showings of the remainder of sidewall and inner bead are included for the purpose of illustrating environment and form no part of the claim.

1 Claim, 3 Drawing Sheets

FIG. 1

FIG. 2

FIG. 3
